A. VANGEN

SELF INDICATING TARGET

Filed Aug. 29, 1922

Inventor
Anton Vangen
By *Henry Smith* Atty.

UNITED STATES PATENT OFFICE.

ANTON VANGEN, OF VESTMARKEN, NORWAY.

SELF-INDICATING TARGET.

Application filed August 29, 1922. Serial No. 585,051.

To all whom it may concern:

Be it known that I, ANTON VANGEN, a subject of the King of Norway, residing at Vestmarken, Norway, have invented certain new and useful Improvements in Self-Indicating Targets; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to selfmarking targets of the kind which is specified and illustrated in my U. S. Patent No. 1,222,822. In the usual form of this selfmarking target the ring sections of the target engage impact rods which are actuated by the impact of the bullet against the target section, and which in turn serve to actuate the indicators.

The present invention has for its object an improvement in the connection between the said impact rods and the section indicators, the invention also enabling the values of the several hits to be automatically registered.

This is obtained by connecting the rear ends of the several impact rods with a spider or disc, the center of which engages a device serving to actuate the value indicator or a registering apparatus.

The indicators for the position of each hit on the target section are as usual actuated by each individual rod or by the movement of the connecting point between each individual impact rod and the spider or disc connecting the rear ends of the same.

On the drawing is diagrammatically illustrated a form of the invention.

1 is a target disc, and 40 indicates the four impact rods connected with the same. 7 is the central supporting rod for the disc sections, said rod being partly broken away for the sake of clearness. 76 is a helical spring serving to maintain disc 1 in its position on the rod 7. The impact rods 40 are as usual provided with abutments 45, serving to actuate the auxiliary indicators

which mark the position of the point hit on the target section.

Behind disc 1 the impact rods are connected with the auxiliary section or spider 55 80, the center 81 of which serves to actuate the section indicator, said center 81 performing a rearward movement irrespective of the point in which section 1 is hit, as a rearward movement of any of the impact 60 rods 40 will cause a rearward movement of center point 81.

The movement of center point 81 may be utilized so as to actuate a visible indicator 65 in the manner illustrated in my above mentioned previous Patent No. 1,222,822, or as indicated on the drawing the movement of the center point 81 may be transmitted to an electric contact device 83 by means of a pivoted bell crank lever 82 in order to 70 obtain an automatic registration of the hit.

Claims:—

1. A self-indicating target comprising a target section, and an auxiliary section behind the latter, both capable of axial and 75 tilting movement, a plurality of parallel rods connected to the sections near the outer portions thereof, and an indicating device operable by the axial movement of the auxiliary section.

2. A self-indicating target comprising a yieldingly supported annular target section capable of axial and tilting movement, an auxiliary section having a plurality of radial arms mounted axially of and behind the target section, a plurality of parallel impact rods connected to said arms and to the target section near the periphery of the latter, a pivoted bell-crank lever having one arm terminating at the axis of the auxiliary section and operable by the movement of the latter, and an indicating device operable by the movement of the other arm of said lever.

In testimony that I claim the foregoing 95 as my invention, I have signed my name in presence of two subscribing witnesses.

ANTON VANGEN.

Witnesses:

J. M. ISMOND,
DAGNY SYVERSEN.
